UNITED STATES PATENT OFFICE.

DANIEL HUNSMERGER, OF ROYERSFORD, PENNSYLVANIA.

WALL-HYDRANT.

No. 926,190.

Specification of Letters Patent.

Patented June 29, 1909.

Application filed April 16, 1908. Serial No. 427,548.

To all whom it may concern:

Be it known that I, DANIEL HUNSMERGER, a citizen of the United States, residing at Royersford, in the county of Montgomery and State of Pennsylvania, have invented 5 certain new and useful Improvements in Wall-Hydrants, of which the following is a specification.

My invention relates to an improvement 10 in wall hydrants, and the object is primarily for the attachment of a hose for washing and sprinkling, whereby the water can be obtained from the outside without the necessity of entering the house.

15 The invention consists in certain novel features of construction and combinations of parts which will be hereinafter described and pointed out in the claim.

In the accompanying drawings:—Figure 20 1 is a perspective view. Fig. 2 is a longitudinal section. Fig. 3 is a detail.

A, represents the bib or casting having the flange 1 which is adapted to be placed against the wall of a building, and 2, is 25 the end to which the water passes and to which a hose can be attached. The bib or casting A is connected to a horizontal pipe 3 which passes through the wall of the building and connected to the end of the pipe 30 3 is a coupling 4. Connected to the coupling is the water supply pipe 5.

Extending through the pipe 3 and the bib, is a valve stem 6 which has screw-threads 7 engaging the screw-threads 8 in 35 the bib or casting A, and a cap 9 is received on the valve stem and screwed onto the casting A for closing the end.

A wheel 10 on the outer end of the valve stem is adapted to operate the same through 40 screw-threaded connections on the valve stem and bib. The inner end of the valve stem 6 is provided with a washer forming a valve 11. The valve 11 is adapted to engage the end of the supply pipe 5 which is 45 received in the coupling 4 which forms a valve seat for the valve whereby the water is prevented from entering pipe 3.

When it is desired to obtain water, the

wheel 10 is turned, causing the valve 11 to be removed from its seat through screw-threaded connections of the valve stem and bib, whereby the desired supply of water is obtained from the supply pipe, 5, through pipe 3, passing through the nozzle 2, of the 50 55 bib.

From the foregoing it will be seen that I have provided a simple and efficient wall hydrant by means of which various objects of the invention may be attained during all seasons of the year, and there will be no 60 danger of the pipe freezing if the supply pipe is closed on the inner wall of the house instead of closing it as it passes through the wall.

It is evident that more or less slight 65 changes might be resorted to in the form and arrangement of the several parts described without departing from the spirit and scope of my invention, and hence I do not wish to limit myself to the exact construction herein set forth, but:—

Having fully described my invention, what I claim as new and desire to secure by Letters Patent, is:—

In a wall hydrant, the combination with a 75 wall pipe and a bib connected to one end thereof, of a supply pipe having a reduced end, a coupling internally screw-threaded at both ends adapted to receive the end of the wall pipe and the reduced end of the supply 80 pipe for connecting the two pipes, said coupling being of the same internal diameter throughout its length, and a valve stem having screw threaded engagement with the bib, and a valve of less diameter than the interior 85 of the coupling on the end of the valve stem adapted to be seated on the end of the supply pipe entering the coupling, and means for operating the valve stem.

In testimony whereof I affix my signature 90 in presence of two witnesses.

DANIEL HUNSMERGER.
